Letters Patent, No. 2358, Dated July 17, 1866.

Design for Paper Collars.

The schedule referred to in these Letters Patent and making part of the same.

To all whom it may concern:

Be it known that I, B. G. Briggs of Providence in the County of Providence and State of Rhode Island have invented a Design for Paper Collars, and I do hereby declare that the following is a full, clear and exact description thereof, which will enable others skilled in the art to make and use the same, reference being had to the accompanying drawing forming part of this specification.

The drawing represents a perspective view of this invention. This invention relates to a paper collar which is ornamented by medallions, each containing a head in such a manner that a collar is obtained which presents a novel and elegant appearance.

A, represents a paper collar which is ornamented by medallions B. These medallions are surrounded by borders and they contain heads as shown.

What I claim as new and desire to secure by Letters Patent is, the Design for a paper collar as shown and described.

The above Specification of my invention signed by me this 7th day of June 1866.
